(57) **CLAIM**

The ornamental design for a carrier for containers, as shown and described.

DESCRIPTION

FIG. 1 is a perspective view of a carrier for containers showing our new design, shown in a position of use with exemplary containers.

FIG. 2 is a left elevation view thereof, the right elevation view is a mirror image.

FIG. 3 is a front elevation view thereof, the rear elevation view is a mirror image.

FIG. 4 is a top plan view thereof.

FIG. 5 is a bottom plan view thereof; and,

FIG. 6 is a plan view thereof, shown independent of the exemplary containers to show aspects of the design not visible when combined, and further in an unfolded configuration.

The broken lines are shown for the purpose of illustrating both parts of the article as well as exemplary environmental subject matter of containers. None of the broken lines form part of the claimed design. The horizontal dashed lines in FIG. 5 represent fold lines and form no part thereof.
